UTILITY POLE GUY HOOK

Joseph W. Dimiceli, 417 Eccles Ave.,
South San Francisco, Calif. 94080

Continuation of abandoned design application Ser. No.
273,058, July 1, 1972. This application Nov. 14, 1973,
Ser. No. 415,587

Term of patent 14 years

Int. Cl. D8—08

U.S. CL. D8—260

FIG. 1.

FIG. 2.

FIG. 1 is an isometric view of the utility pole guy hook of my invention.

FIG. 2 is a perspective diametrically opposite to the view shown in FIG. 1 of the utility pole guy hook of my invention.

This application is a continuation of design application Ser. No. 273,058, filed July 1, 1972, now abandoned.

I claim:

The ornamental design for a utility pole guy hook, as shown.
